COMBINED LATHE, PRESS, AND JIG SAW

Homer Emrick, Kalamazoo, Mich., assignor to Emrick,
Inc., Kalamazoo, Mich., a corporation of Michigan

Application October 19, 1953, Serial No. 27,216

Term of patent 14 years

(Cl. D54—6)

Fig. 3

Fig. 2

To all whom it may concern:

Be it known that I, Homer Emrick, a citizen of the United States of America, residing at Kalamazoo, in the county of Kalamazoo, State of Michigan, have invented a new, original, and ornamental Design for a Combined Lathe, Press and Jig Saw, of which the following is a specification, reference being made to the accompanying drawings, forming a part thereof.

In the drawings:

Fig. 1 is a perspective view of a combined lathe, press and jig saw embodying my new design;

Fig. 2 is a side elevational view thereof. The other side is substantially the same;

Fig. 3 is a top plan view thereof;

Fig. 4 is an elevational view taken from the right end of Fig. 2 with the dead spindle removed; and

Fig. 5 is an elevational view taken from the left end of Fig. 2.

I claim:

The ornamental design for a combined lathe, press, and jig saw, substantially as shown and described.
